UNITED STATES PATENT OFFICE.

FREDERICK SCHWARTZ, OF BROOKLYN, NEW YORK.

DESIGN FOR A LIGHT-GLOBE.

51,890.

Specification for Design.

Patented Mar. 19, 1918.

Application filed March 9, 1917. Serial No. 153,769. Term of patent 7 years.

To all whom it may concern:

Be it known that I, FREDERICK SCHWARTZ, a citizen of the United States, and a resident of the borough of Brooklyn, county of Kings, and State of New York, have invented a new, original, and ornamental Design for a Light-Globe, of which the following is a specification, reference being had to the accompanying drawing, forming a part hereof.

The figure of the drawing is a side elevation of the light globe, the lower portion being indicated by a dotted line.

1 is the lower part of the globe. It is in the form of a hollow bowl.

2 is the upper portion of the globe. It is conoidal in form and its lower portion flares outward to meet the upper edge of

the bowl 1, as indicated. Any projection of the upper part 2 defines concave lines. The part 2 is surmounted by a cap 3 having a collar 4. 5 is an annular ring which surrounds the meeting edges of the parts 1 and 2.

The parts 1 and 2 are generally made of glass and the parts 3 and 5 are generally made of metal.

I claim:

The ornamental design for a light globe having the shape and configuration substantially as shown and described.

FREDERICK SCHWARTZ.

Witnesses:

HELEN M. DANIELS,
IDA G. GILMORE.
